UNITED STATES PATENT OFFICE

GEORGE L. FULK, OF CLEVELAND, OHIO, ASSIGNOR, BY MESNE ASSIGNMENTS, TO BONNAR-VAWTER FANFORM COMPANY, INC., OF CLEVELAND, OHIO, A CORPORATION OF DELAWARE

FOLDING MACHINE

Application filed September 21, 1926. Serial No. 136,798.

The present invention relates to a folding machine adapted to fold a sheet of indeterminate length along a series of longitudinal lines into a series of superposed layers or leaves, and is designed particularly for use in producing fanforms for waybills, order blanks, invoices, collection forms and the like, which are adapted to receive carbon paper between the leaves for producing duplicate 10 copies.

The machine of the present invention is adapted to receive the paper directly from the printing press, which applied the printed matter to successive areas in parallel rows 15 along the length of the sheet.

One of the main objects of the invention is to provide means for continuously folding the sheet along longitudinal lines between the rows of printed matter in such manner that 20 the printed matter on the superposed leaves of the folded sheet will be in perfect registry.

The invention has for a further object to provide means for forming transverse perforated lines in the superposed leaves of the 25 sheet at intervals along the length thereof to permit the individual forms to be readily detached.

A further object is to provide means for punching holes through the superposed leaves 30 at predetermined points along the length of the sheet.

A further object is to provide perforating and punching means adapted to operate upon the folded sheet while the same is in continuous movement through the machine.

A further object is to provide a machine which can be readily adjusted for sheets of different widths and for producing a greater or less number of folds in the sheet.

40 A further object is to provide a folding, perforating and punching machine in which the paper is maintained at all times under tension so that proper registry is maintained between the printed matter on the superposed leaves.

With the above and other objects in view, the invention may be said to comprise the machine as illustrated in the accompanying drawings hereinafter described and particularly set forth in the appended claims, to-

gether with such variations and modifications thereof as will be apparent to one skilled in the art to which the invention appertains.

Reference should be had to the accompanying drawings forming a part of this specification, in which:

Fig. 1 is a top plan view of the machine;

Fig. 2 is a side elevation of the machine;

Fig. 3 is a section taken on the line indicated at 3-3 in Fig. 1;

Fig. 4 is a section taken on the line indicated at 4-4 in Fig. 1;

Fig. 5 is a section taken on the line indicated at 5-5 of Fig. 1;

Fig. 6 is a section taken on the line indicated at 6-6 of Figs. 2 and 3;

Fig. 7 is a section taken on a line indicated at 7-7 in Figs. 2 and 4;

Fig. 9 is a section taken on a line indicated at 9-9 in Figs. 2 and 5;

Fig. 10 is a section taken on a line indicated at 10-10 in Fig. 2;

Fig. 11 is a fragmentary plan view on an 75 enlarged scale showing the forward folding frame and the perforating device;

Fig. 12 is a view partly in side elevation and partly in vertical section of the portion of the machine shown in Fig. 11;

Fig. 13 is a fragmentary section taken on the line indicated at 13-13 in Fig. 11;

Fig. 14 is a rear elevation of the punching mechanism;

Fig. 15 is a top plan view of the punching 85 mechanism, parts thereof being broken away and shown in section;

Fig. 16 is a detail view showing the adjustable connection between one of the form supporting rods and the frame of the machine.

Fig. 17 is a side elevation partially in section showing the feed rollers and their driving connections.

Fig. 18 is a section on line 18-18 of 95 Fig. 17.

Referring to the accompanying drawings, the machine of the present invention is mounted upon an elongated frame 1, the rear end of which adjoins the discharge end 2 of 100

a printing press designed to print duplicate forms on a sheet as it passes through the press, the sheet as it passes through the delivery roll 3 of the printing press passing directly into the folding machine.

5 The frame 1 of the machine is provided with a series of longitudinally spaced pairs of standards 4, 5, 6 and 7, between which are supported fixed folding forms 8, 9 and 10 through which the sheet is passed and which act upon the sheet as the sheet is drawn through the machine to fold the sheet into a series of superposed leaves or layers.

15 The number of forms employed depends upon the number of folds to be made in the sheet and while the accompanying drawing shows three forms, it is to be understood that the number of forms employed depends upon the number of folds to be made in the sheet.

20 The form 8, at the entrance end of the machine has the shape of an isosceles trapezoid arranged with its wide end or base at the entrance end of the machine.

25 The form 9 is also substantially of the shape of an isosceles trapezoid with its wide end or base adjacent the narrow end of the form 8 and of substantially the same width.

30 The form 8 is supported in a position downwardly inclined toward the front of the machine, and the form 9 is supported at an inclination reverse to that of the form 8 and the sheet in passing through these forms passes beneath the form 8 and along the top of the form 9.

35 The third form 10 has the shape of an isosceles triangle and is arranged with its base adjacent to and of the same width as the small end of the form 9, the form 10 being inclined downwardly toward the forward end of the machine.

40 The first form 8 is supported at its rear end adjacent the entrance end of the machine by means of arms 11, fixed to the frame and extending upwardly and rearwardly from the upper side thereof and resting on a rod 12 extending between the upper ends of the standards 4, the arms 11 having sockets or recesses 11^a to receive the rod 12 and set screws 11^b for securing the arms in adjusted position on the rod. By adjusting the set screws 11^b, the rear ends of the form 8 may be adjusted slightly up or down to properly accommodate the sheet being folded.

45 The lower forward end of the form 8 is provided adjacent opposite sides thereof with upwardly extending arms 13 provided with openings to receive a horizontal cross-rod 14 extending between the sides of an inner guide frame 15 which has vertical sides substantially in alignment with the forward corners of the form 8 and a bottom guide plate 16, the under surface of which is horizontal and aligned with the lower forward edge of the frame 8, the guide frame 15 being suspended from a cross-rail 17 connect-

50 ing the upper ends of the standards 5 at opposite sides of the supporting frame. As the paper passes beneath the tapered form 8, the edge portions of the sheet are turned upwardly into vertical planes and are guided and held in a vertical position as they pass along the outer side of the inner guide frame 15 by means of vertical guide posts 18 which engage the outer side of the sheet, the opposite converging sides 19 of the form 8 having their outer surfaces disposed in vertical planes to assist in guiding the paper into the space between the guide post 18 and sides of the guide frame 15.

55 The form 9 which is disposed at an inclination opposite that of the form 8 has side members 20 whose outer faces are also disposed in vertical planes to assist in holding the portion of the sheet overlying the opposite sides of the form in a vertical plane.

60 The lower rear end of the form 9 is supported adjacent the lower ends of the standards 5 by means of downwardly projecting ears 21 and a rod 22 extending between the standards 5 and passing through the ears 21. To permit adjustment of the form 9, the rod 22 is provided with eccentric bearing portions 22^a which are held in adjusted positions in bearings 22^b by means of set screws 22^c, the adjustment of the rod in its bearings causing the rod and the rear end of the form 9 to be raised or lowered. The upper forward end of the form 9 is supported from an inner guide frame 23 by means of ears

65 24 projecting from the forward end of the frame and a rod 25 carried by the frame 23 and passing through the ears. The frame 23 also serves to guide the opposite vertically disposed edge portions of the sheet and has opposite side walls whose outer surfaces are disposed in the same vertical plane as the forward corners of the form 9. The frame 23 also has a horizontal upper guide plate 26 whose upper surface is in the same horizontal plane as the upper forward edge of the form 9, the guide frame 23 being supported upon a bottom plate 27 extending between the standards 6.

70 In passing over the form 8 and between the guide posts 18 and guide frame 15, the sheet has its opposite edge portions turned upwardly into a vertical plane and in passing over the form 9, a second leaf is folded into a vertical plane within the vertical outer edge portions of the sheet.

75 The triangular form 10 is supported at its rear end from the upper ends of the standards 6 by means of arms 28 attached to the form and cross-rod 29 extending between the upper ends of the standards and through the arms 28, the arms 28 being adjustably supported on the rod 29 by means of set screws 28^a. The form 10 is inclined downwardly toward the forward end of the machine and is supported by means of an arm 30 rigidly

attached thereto and extending upwardly from the forward end of the form 10 which lies between the supporting standards 7. The forward end of the form 10 is supported by means of a shaft 31 which passes through the upper end of the arm 30 and has eccentric bearing portions 31^a journaled in the upper portions of the standards 7, the eccentric mounting of the shaft 31 permitting a slight vertical adjustment of the forward end of the form 10. The paper in passing from the form 9 to the form 10 passes between the side walls of the guide frame 26 and vertical guide frame 32 adjacent thereto, so that the sheet 15 is fed to the form 10 with the two folded leaves on the opposite sides thereof held in a vertical plane. As the sheet passes over the form 10, the central portion of the sheet passing beneath the form is doubled upon itself so that as the sheet is drawn past the apex of the form, the central portion of the sheet is folded upon itself along a central longitudinal line and the two leaves so formed are in a vertical plane between the outer leaves 25 folded by the preceding forms, the sheet being now folded into six superposed layers or leaves all disposed in a vertical plane immediately adjacent the apex of the form 10 where a pair of closely spaced creasing guides 33 bear against opposite sides of the folded sheet to press the leaves together and form sharp creases along the folded lines.

The sheet is continuously drawn through the forms by means of feed rollers 34 adjacent the forward end of the machine, these rollers being arranged in pairs and engaging opposite sides of the folded sheet adjacent the upper and lower edges thereof. The feed rollers 34 are mounted upon parallel vertical shafts 35 and 36 and the shaft 35 is driven by means of a bevel gear 37 at its lower end which meshes with a bevel gear 38 fixed to a transverse driven shaft 39, which is driven from any suitable source of power. The shaft 36 is driven from the shaft 35 by means of a gear 40 fixed to the shaft 35 and a gear 41 fixed to shaft 36 and meshing with the gear 40.

In order to keep the fold lines straight, it is essential that the sheet be kept accurately aligned with the forms and in the present invention lateral movements of the sheet are prevented by maintaining the sheet, while passing through the machine, under a uniform tension. This tension is maintained by the feed rollers which have a frictional slip connection with the shafts upon which they are mounted so that speed of rotation of the rollers can lag behind the speed of rotation of the shafts which are driven at a rate to impart a normal peripheral speed to the rollers which is slightly in excess of the speed of movement of the sheet. The rollers 34 are loosely mounted upon sleeves 34^a fixed to the shafts 35 and 36, each sleeve being fixed to its shaft and having a flange 34^b at one end and a nut 34^c at the other. One of the rollers 34 is mounted on each sleeve and held between flange 34^b and a friction disk 34^d by coil springs 34^e interposed between the disk nut 34^c and a collar 34^f fixed to the end sleeve 34^a below the disc 34^d. The rollers are thus frictionally gripped between the nut 34^c and flange 34^b, the yielding pressure of the springs 34^e permitting the rollers to slip on the sleeves so that excessive tension on the paper sheet is prevented. The tension of the springs 34^e can be varied by adjusting the nut 34^c and by increasing or decreasing the tension of the springs, the pull exerted by the rollers on the sheet can be varied.

In order that the folded sheet may be yieldably gripped between the opposed feed rollers, the shaft 36 is mounted in slidable bearing blocks 36^a, which are yieldably pressed 85 toward the shaft 35 by compression springs 36^b.

Prior to starting the machine in operation, the end of a sheet passing through the printing press is pulled forwardly by hand beneath the form 8, the opposite edge portions being turned up along the opposite converging sides 19 of the form, as shown in Fig. 6, and passed between the guide posts 18 and opposite sides of the inner guide frame 15, beneath the bottom guide plate 16 of the guide frame 15 and along the top of the form 9. As the sheet is drawn over the form 9, the sheet is folded as it passes over the converging sides thereof, forming a second vertical layer within the 100 first on each side of the sheet, as shown in Figs. 7 and 8, the two superposed layers being guided between the vertical guide posts 32 and the sides of the inner guide frame 23 at the forward end of the form 9; the sheet 105 as it approaches the forward end of the form 9 assuming the position shown in Fig. 8 of the drawing. The sheet is then guided between the guide posts 32 and guide frame 23 and beneath the form 10 with the two folded leaves on opposite sides of the sheet held in a vertical plane. As the sheet is pulled along the tapered form 10, the central portion of the sheet is folded down along the inner side of the folds at opposite edges of the sheet, as 110 shown in Fig. 9, and when the sheet has passed the apex of the form, the sheet will have been folded into six layers as shown in Fig. 10. The folded sheet is then drawn forwardly and inserted between the feed rollers 34 after which the feed rollers may be driven to continuously draw the sheet through the machine. The sheet is guided into the machine over a roller 42 suspended from the cross-rod 12, at the rear end of the machine, 115 and is discharged from the machine over an inclined cylindrical guide member 43 which serves to turn the folded sheet into a plane at right angles to that of the folded sheet in the machine so that it can be conveniently 120

125

130

folded along transverse lines and delivered into a suitable receiving receptacle.

In order to permit the forward end of a sheet to be easily threaded through the machine by hand, the guides 33 are pivotally supported on the frame at 33^a to swing about vertical axes toward and from each other so that they can be readily separated to permit insertion of the folded sheet between them. 10 To facilitate the insertion of the forward end of the sheet between the feed rollers, a lever 36^a is pivotally mounted on the frame in a position such that it may be swung into engagement with one of the movable bearings 36^b of the shaft 36 to shift the shaft away from the shaft 35 in opposition to the springs 36^b to separate the feed rollers.

In addition to the folding mechanism above described, the machine is provided 20 with means for forming transverse lines of perforations in the superposed leaves of the folded sheet at regularly spaced intervals along the length thereof. For forming the transverse lines of perforations, a pair of 25 vertically disposed cylinders 44 and 45 are provided between the folding forms and feed rollers a short distance in front of the creasing guides 33 and these drums are positioned to receive the folded sheet between them. 30 The cylinder 44 is mounted upon a vertical shaft 46 which is drawn by means of a worm gear 47 fixed thereto and a worm 48 fixed to a horizontal shaft 49 which is provided at the end thereof with a bevel gear 50 which 35 meshes with a bevel 51 fixed to a transverse countershaft 52 which is driven from the main drive shaft 39 by means of a sprocket chain 53 running over suitable sprockets on the shafts 39 and 52. The opposite cylinder 40 45 is driven from the cylinder 44 by means of a spur gear fixed to the lower end of the cylinder 44 which meshes with a similar spur gear fixed to the lower end of the cylinder 45. The operation of the perforating cylinders 45 is controlled by a clutch 51^a coacting with the gear 51 on the shaft 52 so that the cylinders can be thrown out of operation when desired. The cylinder 44 is the knife cylinder and is provided with a series of spaced 50 vertical knife receiving grooves in its periphery which are adapted to receive serrated perforating knives 57, which are placed in selected grooves 56 which are so spaced as to bring the knives into engagement with the folded sheet at the desired points along the length thereof. By setting the knives 57 in the proper grooves 56, the lines of perforations in the sheet may be made at the desired distances apart. The cylinder 45 is the tympan and is provided with a relatively soft metal covering 58, preferably of copper. As 55 the folded sheet passes between the cylinders 44 and 45, the knives 57 are successively brought into engagement with the sheet and 60 form the lines of perforations extending

transversely across each of the leaves of the folded sheet.

For convenience in filing the printed forms, it is desirable that they be provided with holes adjacent the tops thereof and to accomplish this purpose, means is provided for punching a single hole or a pair of holes at the desired points between the rows of transverse perforations, the punching means being located between the perforating drums and the feed rollers 34. The sheet punching mechanism is mounted in a vertical guide frame having four vertical angle posts 59 and includes an upper punch supporting frame 60 and a lower punch supporting frame 61, these frames being mounted for independent vertical adjustment within the angle guide posts 59 and secured in adjusted position to the posts by means of bolts 62 which are passed through the holes 63 in the posts 59, the holes 63 being closely spaced throughout the length of the post so that each frame can be secured in any desired position of vertical adjustment.

The upper frame carries a horizontal shaft 64 and the lower frame carries a horizontal shaft 65 and both shafts being disposed transversely of the frame 1. The shafts 64 and 65 are driven by means of worm gears 66 and 67 affixed thereto and meshing with vertically disposed worms 68 and 69 which are rotatably mounted in the frames 60 and 61. The two worms 68 and 69 are simultaneously driven by means of a vertical shaft 70 extending through the two worms and slidably keyed to both. The slideable connection between the shaft 70 and the worms 68 and 69 permit adjustment of the punch frames without disturbing the driving connection. The shaft 70 has a bevel gear 71 at its lower end which 105 meshes with a bevel gear 72 and the countershaft 52.

Punching devices are mounted upon each of the shafts 64 and 65 and, since the two punching devices are identical, a description of one will suffice for both and like parts in the two devices will be indicated by the same reference numerals.

A pair of spaced disks 73 and 74 are mounted on the outer ends of each of the shafts 64 and 65 and the inner disks 73 carry one or more punches 75 which are slidably mounted in bores formed in the disk adjacent the periphery and parallel with the axis of the disks. The punches are normally held in retracted positions by means of compression springs 76 which are interposed between an enlarged portion 77 of the punch and the bottom of a counterbore in the disk in which the enlarged portion 77 slides. The punches 115 are detachably mounted in the disks by means of removable caps 78 and each of the punches has a reduced outer end portion 79 which extends through a central opening in the cap. The two disks 73 and 74 of each punching 120

device are spaced apart just a sufficient distance to permit them to straddle the folded sheet and the punches are operated to perforate the leaves of the sheet by means of 5 cam rollers 80 which are mounted in brackets 81 fixed to the frames 60 and 61.

When the projections 79 of the punches engage with the rollers 80, the punches are forced outwardly through the folded sheet to 10 form the holes in the sheet, the outer disks 74 being provided with apertures 82 registering with each of the punches so that the paper removed in punching the holes may be discharged through these apertures. The cam 15 roller 80 of the upper punch frame is disposed immediately below the shaft 64 so that the punch is operated while the peripheral portion of the disk carried in the punch is traveling in the same direction as the folded 20 sheet and the gearing for driving the disks is so timed with respect to the rate of movement of the sheet that the punch and sheet are traveling at substantially the same rate during the punching operation. The cam 25 roller of the lower punch frame is disposed directly above the shaft 65 and the operation is identical with that of the punching device carried by the upper frame. Either or both of the punching devices can be adjusted to 30 a position entirely clear of the sheet, either of the punching devices may be used alone, or the two punching devices may be operated simultaneously. The adjustment of the punch frames permits the holes to be formed in the 35 sheet at any desired distance from the edge thereof, either punching device being operable to punch the holes in different positions between the center and edge of the sheet.

The sheet as it is fed through the printing 40 press with the proper printing matter for the fan folded forms thereon is continuously folded as it is drawn through the fixed forms along lines between the rows of printed matter on the sheet. The sheet is perforated 45 along transverse lines to permit separation of the fan folded forms one from another and each form may be provided with one or more holes at the desired point or points in the body thereof for convenience in filing.

50 The forms are readily removable and may be replaced with forms suitable for wider or narrower sheets. The three forms shown in the drawing are adapted to fold the sheet into six leaves of equal width when the width 55 of the sheet is equal to the width of the first form 8 at its wide end. A sheet of the width required to fold into five leaves of the same width, as the sheet above described, may be folded into five widths by the same forms by 60 feeding the paper over the first form 8 with one of its edges in alignment with one corner of the form at the entrance end thereof. A sheet having the width of four or three leaves 65 will pass over the central portion of the first form and be folded in passing over the second

and third forms and a sheet of the width of two leaves will pass over the central portions of the first two forms and be folded by the third triangular form.

It will be apparent that by providing forms of the proper size a sheet of any width may be folded into the desired number of leaves.

It will be apparent that, if each form is set at an angle to the horizontal equal to one-half of the angle of convergence of its sides, 75 opposite portions of the sheet after having passed over a side edge of a form will travel in vertical planes contacting with the sides of the forms, since the distance along the line of intersection of a horizontal plane with the 80 planes of the sides of the form from any point along the length thereof to the apex or narrow end 10 is exactly equal to the distance along the line of intersection of the central vertical plane with the plane of the top or 85 bottom guide face thereof from a corresponding central point to the apex of the form 10, therefore, equal tension may be maintained throughout the width of the sheet as it passes over the forms.

In passing over the forms the edge portions of the sheet are caused to progressively bend into a plane at right angles to the central portion thereof and the central portion of the sheet is caused to change its direction 90 of movement as it passes over the end of the form. The sheet is thus progressively flexed along two intersecting lines and since the material of a sheet, particularly a paper sheet is not perfectly flexible there is necessarily an added strain on the material thereof in the portion passing through the points of intersection of the lines of bend at the corners of the forms. It is of course essential 95 in a machine of this character that the design be such that the sheet will not be subjected to strains liable to tear or damage the same or which would tend to shift the sheet out of alignment in its passage over the forms. One of the most important features of the 100 present invention is the guide structure between adjacent forms by which the sheet is guided from one form to the other in such manner that the material of the sheet is not subjected to excessive strains. The horizontal 105 guide members 16 and 26 serve to guide the middle portion of the sheet in horizontal planes between successive forms so that the sheet, instead of passing directly from one form to the next, passes from one inclined 110 guide portion to a horizontal guide portion and from the horizontal guide portion to the next inclined portion, and, instead of having a transverse bend equal to the angle between 115 successive forms and single and double edge folds traveling on successive forms in substantially straight lines, has two separate transverse bends each equal to one-half of the angle between the forms and edge por- 120 125 130 135

tions on successive forms traveling along lines offset with respect to each other.

The side portions 15 and 23 of the intermediate guide frames and the guide posts 5 18 and 32 cooperating therewith serve to cause the folded edge portions coming from the inwardly converging sides of one form to travel in a direction parallel with the longitudinal center line of the sheet to the wide 10 end of the next form.

The small angles of bend between the inclined forms and straight guides permit the paper or other sheet material to accommodate itself during its travel to the corners of the 15 forms and to pass over these corners without being subjected to excessive strains, the distance between the transverse bend lines at opposite edges of the straight guide frame members being sufficient to permit the sheet 20 to conform thereto and be positively guided thereby. The intermediate guide frames also serve to positively hold the folded edge portions against shifting up or down out of the proper line of travel and prevent creeping 25 of the portions of the sheet in engagement with sides of the forms, thus insuring straight creases and leaves of uniform width.

Having thus described my invention, I claim:

30. 1. In a folding machine, means for continuously feeding a sheet to be folded, means acting on opposite edge portions of the sheet as it is being fed to progressively and successively bend said edge portions into a plane 35 at right angles to the body of the sheet in alternating directions, and means acting upon the sheet between said edge portions to fold the same into a plurality of layers between said edge portions.

40. 2. In a folding machine, means for continuously feeding a sheet to be folded, means acting on opposite edge portions of the sheet as it is being fed to progressively and successively bend said edge portions into a plane 45 at right angles to the body of the sheet in alternating directions, guiding means for retaining said edge portions of the sheet in said plane and for guiding said edge portions toward the center of the sheet, and 50 means acting upon the central portion of the sheet to simultaneously fold the same into a plurality of layers between said edge portions.

55. 3. In a folding machine, a series of forms over which a sheet to be folded is drawn, said forms tapering in the direction in which the sheet is drawn, the first form over which the sheet passes being of a width at its entrance end substantially equal to the width of the 60 sheet, the wide end of each subsequent form being substantially equal in width to the narrow end of the preceding form, and inclined oppositely with respect thereto, the last form over which the sheet passes being 65 triangular, and means for alternately draw-

ing the sheet through the machine over and beneath alternate forms, and for progressively turning the portions of the sheet passing over the tapering edges of the forms into planes at right angles to the inner portions of the sheet.

4. In a folding machine, a plurality of forms adapted to fold a sheet drawn therethrough along a plurality of longitudinal lines, means engageable with the folded sheet to draw the sheet through the forms, and means for perforating the superposed leaves of the folded sheet.

5. In a folding machine, a plurality of forms adapted to fold a sheet drawn therethrough along a plurality of longitudinal lines, means engageable with the folded sheet to draw the sheet through the forms, and means interposed between the sheet drawing means and forms for perforating the superposed leaves of the folded sheet.

6. In a folding machine, a plurality of forms adapted to fold a sheet drawn therethrough along a plurality of longitudinal lines, means engageable with the folded sheet to draw the sheet through the forms, and means for forming a line of perforations in the superposed leaves of the folded sheet.

7. In a folding machine, a plurality of forms adapted to fold a sheet drawn therethrough along a plurality of longitudinal lines, means engageable with the folded sheet to draw the sheet through the forms, and means for forming transverse lines of perforations in the superposed leaves of the folded sheet at predetermined intervals along the length thereof.

8. In a folding machine, a plurality of forms adapted to fold a sheet drawn therethrough along a plurality of longitudinal lines, means engageable with the folded sheet to draw the sheet through the forms, a pair of opposed cylinders on opposite sides of the folded sheet between the forms and the sheet drawing means, a serrated knife carried by one of the cylinders, and means for driving the cylinders.

9. In a folding machine, a plurality of forms adapted to fold a sheet drawn therethrough along a plurality of longitudinal lines, means engageable with the folded sheet to draw the sheet through the forms, and means interposed between the sheet drawing means and forms for punching holes through the superposed leaves of the folded sheet at regularly spaced points along the length thereof.

10. In a folding machine, a plurality of forms adapted to fold a sheet drawn therethrough along a plurality of longitudinal lines, means engageable with the folded sheet to draw the sheet through the forms, a punch interposed between said drawing means and forms, and means for actuating the punch to form holes through the superposed leaves of

the folded sheet at predetermined points along the length thereof.

11. In a folding machine, means for delivering a sheet of uniform width and indeterminate length in a horizontal plane to said machine, folding means for progressively folding the sheet along longitudinal lines and for guiding the superposed leaves as they are folded into a vertical plane, opposed vertical power driven feed rollers engageable with opposite sides of the folded sheet for drawing the same through the folding means, and means interposed between the feed rollers and folding means for perforating the superposed leaves of the folded sheet.

12. In a folding machine, means for delivering a sheet of uniform width and indeterminate length in a horizontal plane to said machine, folding means for progressively folding the sheet along longitudinal lines and for guiding the superposed leaves as they are folded into a vertical plane, opposed vertical power driven feed rollers engageable with opposite sides of the folded sheet for drawing the same through the folding means, a punch having dies upon opposite sides of the vertically disposed folded sheet between the folding means and feed rollers, and means for actuating said punch to form holes through the superposed leaves at predetermined points along the length of the sheet.

13. In a folding machine, means for delivering a sheet of uniform width and indeterminate length in a horizontal plane to said machine, folding means for progressively folding the sheet along longitudinal lines and for guiding the superposed leaves as they are folded into a vertical plane, opposed vertical power driven feed rollers engageable with opposite sides of the folded sheet for drawing the same through the folding means, a punch having dies upon opposite sides of the vertically disposed folded sheet between the folding means and feed rollers, means for actuating said punch to form holes through the superposed leaves at predetermined points along the length of the sheet, and means for adjusting said punch vertically to vary the position of said holes.

14. A folding machine having means for delivering a sheet of uniform width and indeterminate length in a horizontal plane thereto, folding means for progressively folding the sheet along longitudinal lines and for guiding the superposed leaves as they are being folded into a vertical plane, opposed vertically disposed power driven feed rollers engageable with the opposite sides of the folded sheet for drawing the sheet continuously through the folding means, a pair of spaced vertically disposed disks secured together for simultaneous rotation and straddling the folded sheet between the folding means and feed rollers, means for driving

said disks, a horizontally disposed punch carried by one of said disks, the other of said disks having an aperture aligned with the punch, and a stationary cam for actuating the punch.

15. A folding machine having means for delivering a sheet of uniform width and indeterminate length in a horizontal plane thereto, folding means for progressively folding the sheet along longitudinal lines and for guiding the superposed leaves as they are being folded into a vertical plane, opposed vertically disposed power driven feed rollers engageable with the opposite sides of the folded sheet for drawing the sheet continuously through the folding means, a pair of spaced vertically disposed disks secured together for simultaneous rotation and straddling the folded sheet between the folding means and feed rollers, means for driving said disks, a horizontally disposed punch carried by one of said disks, the other of said disks having an aperture aligned with the punch, a stationary cam for actuating the punch, and means for adjusting the disks and cam vertically as a unit to vary the position of the holes in the sheet.

16. A folding machine having means for delivering a sheet of uniform width and indeterminate length in a horizontal plane thereto, folding means for progressively folding the sheet along longitudinal lines and for guiding the superposed leaves as they are being folded into a vertical plane, opposed vertically disposed power driven feed rollers engageable with the opposite sides of the folded sheet for drawing the sheet continuously through the folding means, means interposed between the feed rolls and folding means for perforating the superposed leaves of the folded sheet along transverse lines, and means for punching a hole through the superposed leaves adjacent each line of perforations.

17. In a folding machine having means for receiving a sheet of uniform width and indeterminate length and folding the same along longitudinal lines into a series of superposed leaves, means for perforating the superposed leaves of the folded sheet along spaced transverse lines, and means for continuously drawing the sheet past the folding and perforating means.

18. In a folding machine having means for receiving a sheet of uniform width and indeterminate length and folding the same along longitudinal lines into a series of superposed leaves, means for perforating the superposed leaves of the folded sheet along spaced transverse lines, means for punching holes in the leaves adjacent the lines of perforations, and means for continuously drawing the sheet past the folding and perforating and punching means.

19. In a machine for folding a sheet along longitudinal lines comprising a plurality of

tapering forms over which the sheet is drawn, said forms having oppositely inclined surfaces over which the sheet travels and forwardly converging sides in planes at right angles to said surfaces, the wide end of one form being of the same width and aligned with the narrow end of the preceding form, a guide frame interposed between the forms and having a face in the same plane as the end edges of the forms, and end faces at right angles to said first mentioned surface and in the planes of the adjacent side edges of the forms and means for drawing the sheet over said forms.

15 20. In a machine for folding a sheet along longitudinal lines comprising a plurality of tapering forms over which the sheet is drawn, said forms having oppositely inclined surfaces over which the sheet travels and forwardly converging sides in planes at right angles to said surfaces, the wide end of one form being of the same width and aligned with the narrow end of the preceding form, a guide frame interposed between the forms 25 and having a face in the same plane as the end edges of the forms, and end faces at right angles to said first mentioned surface and in the planes of the adjacent side edges of the forms, guide members engaging the outside 30 of the sheet for holding the same in engagement with the end faces of the guide frame, and means for drawing the sheet over said forms.

21. In a folding machine, a plurality of 35 forms through which a sheet is drawn, each having sides converging forwardly, each successive form being aligned longitudinally with the preceding form and of the same width at its wide end as the adjacent narrow 40 end of the preceding form, successive forms being oppositely inclined and spaced apart, and means interposed between successive forms for guiding the sheet from one to the other in a direction at an angle to both the 45 adjacent forms.

22. In a folding machine, a plurality of forms through which a sheet is drawn, each having sides converging forwardly, each successive form being aligned longitudinally 50 with the preceding form and of the same width at its wide end as the adjacent narrow end of the preceding form, successive forms being oppositely inclined and spaced apart, and a guide frame between successive forms 55 having vertical guide faces at the sides thereof parallel with the longitudinal center line of the forms and a horizontal guide face extending across the space between the side faces.

10 23. In a folding machine, a form of trapezoidal shape, a form of triangular shape having its base of the same width as the narrow end of the trapezoidal form, said forms being 65 oppositely inclined, and a guide frame between said forms having a guide face in the

plane of the adjacent transverse edges of the forms and guide faces at right angles to said first mentioned face.

24. In a folding machine, a form of trapezoidal shape, a form of triangular shape having its base of the same width as the narrow end of the trapezoidal form, said forms being oppositely inclined, one having a flat upper guide face and the other a flat lower guide face, said forms being oppositely inclined, a guide frame between said forms having a guide face in the plane of the adjacent edges of the forms and side guide faces at right angles thereto, and guide members outside said side faces and parallel therewith.

In testimony whereof, I hereunto affix my signature.

GEORGE L. FULK.
